RUG.

No. 16,890.

Patented Sept. 7, 1886

UNITED STATES PATENT OFFICE.

EMMA J. LAWRENCE, OF PHILADELPHIA, PENNSYLVANIA, ASSIGNOR TO THE HARTLEY CARPET AND RUG COMPANY, OF SAME PLACE.

DESIGN FOR A RUG.

SPECIFICATION forming part of Design No. 16,890, dated September 7, 1886.

Application filed July 8, 1886. Serial No. 207,519. Term of patent 3½ years.

To all whom it may concern:

Be it known that I, EMMA J. LAWRENCE, a citizen of the United States, residing in Philadelphia, Pennsylvania, have invented a new and original Design for a Rug, of which the following is a specification.

My design for a rug is fully shown in the accompanying photographic illustration of three-quarters of the rug, the remaining quarter being a duplication of the end shown. On the background of the center piece are arranged the leaves and flowers of the Easter lily. On the border, at the opposite ends and along one side, are arranged leaves and blossoms, some of which extend over onto the center piece, more particularly at the corners, while a portion of the flowers of the center piece extend over onto the side of the border. On the remaining side of the border are conventional leaves and flowers, alternating with ornaments b, projecting from the margin of the center piece at that side.

I claim—

The herein-described design for a rug, comprising a center piece having the representations of the leaves and flowers of the Easter lily partly extending over onto one border side, while the border has on opposite ends and on one side leaves and flowers, and along the other side leaves and flowers alternating with ornaments b, projecting from the margin of the center piece, all substantially as described and shown.

In testimony whereof I have signed my name to this specification in the presence of two subscribing witnesses.

EMMA J. LAWRENCE.
